(57) **CLAIM**

The ornamental design for a merchandiser, as shown and described.

DESCRIPTION

FIG. 1 is a front, right-side perspective view of a merchandiser that has a second embodiment of the design.

FIG. 2 is a front view of the merchandiser.

FIG. 3 is a rear view of the merchandiser.

FIG. 4 is a right-side view of the merchandiser.

FIG. 5 is a left side view of the merchandiser.

FIG. 6 is a top view of the merchandiser; and,

FIG. 7 is a bottom view of the merchandiser.

The broken lines show elements of the merchandiser that form no part of the claimed design.

1 Claim, 6 Drawing Sheets
